ATTORNEY

UNITED STATES PATENT OFFICE.

CHARLES F. POLK, OF WATERVLIET, NEW YORK.

COLLAR.

1,124,947.

Specification of Letters Patent. Patented Jan. 12, 1915.

Application filed January 25, 1912. Serial No. 673,297.

To all whom it may concern:

Be it known that I, CHARLES F. POLK, a citizen of the United States, residing at Watervliet, county of Albany, and State of New York, have invented certain new and useful Improvements in Collars, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view in perspective of my improved collar. Fig. 2 is a vertical cross-section taken through the back buttonholes of the collar, showing the collar attached to a shirt by means of a button sewed to the back of the shirt below the neckband, which button occupies the button-hole in the tab depending from the band of the collar below the ordinary back button-hole therein. Fig. 3 is a plan view of the back portion of a shirt reinforced and provided below the back buttonhole in the neckband with a button adapted to engage the buttonhole in the tab depending from the band of the collar.

The principal object of the invention is to adapt a collar for use in the ordinary manner if desired and also for attachment to a shirt in such a manner if desired as to avoid the uncomfortable pressure of the back collar-button so commonly experienced with a collar which is attached at the back to the neckband of the shirt in the usual manner; and in the case of a fold-collar to provide an unobstructed tie-space at the back of the collar.

In carrying out my invention in its preferred form, I provide the collar with the usual back buttonhole in its band, and with a buttonholed tab depending from the band immediately below said back buttonhole adapted to receive a button attached to the back of the shirt below the neckband thereof. A collar so made permits of use in the ordinary manner if desired, that is, by buttoning its band at the back directly to the neckband of the shirt by means of a stud or collar-button, while it also permits when desired, attachment of the collar in the pre-

ferred manner herein described without the use of a collar-button at the back of the neckband, thus avoiding the uncomfortable pressure of such a button upon the neck of the wearer and affording an unobstructed space for the tie between the band and the top at the back of the collar.

Referring to the drawings wherein the invention is shown in preferred form embodied in a fold-collar, 1, is the band and, 2, is the folded-over top of the collar having the usual buttonholes in the band at the front, whereby the ends of the collar can be fastened together and to the neckband of a shirt, and also provided with the usual back buttonhole, 3, in the band adapted to receive a stud inserted through a buttonhole, 4, in the neckband, 5, of a shirt, 6, in the usual manner.

In carrying out my invention, I form the band, 1, of the collar with a tab, 7, depending from and below the edge of the band immediately below the ordinary back buttonhole, 3, and I provide said tab with a buttonhole, 8, adapted to receive a button, 9, attached to the back of the shirt below the neckband, 5. To afford a more durable support for the button, 9, a reinforcing-patch, 10, is stitched upon the back of the shirt-body below the neckband; and the button is sewed to this reinforced portion of the shirt as shown in Fig. 3.

My improved collar is preferably worn by attaching the tab, 7, to the button, 9, below the neckband of the shirt thus avoiding the use of a stud or collar-button in the neckband at the back thereof and the consequent pressure of such a button upon the neck. The space between the tab and back of the collar is thus left free and unobstructed to receive and permit sliding adjustment of the necktie, due to the absence of the head of such a collar-button. While having these advantages, my improved collar loses none of the usefulness of the ordinary collar, because in the absence of a button on a shirt below the neckband, the collar may be fastened to the neckband by the usual back stud or button as indicated by dotted lines, 11, in Fig. 2. The collar can thus be worn with any ordinary shirt as well as with a shirt adapted to receive the collar in the preferred manner above described.

I have shown the tab, 7, integral with the band of the collar, but for the purpose for

this invention it is immaterial whether it be so made or made separate and stitched to the band.

Fig. 2 is a diagrammatic view in that no attempt has been made to show the various plies of which the collar and neckband are formed, it being understood that they are made in the usual manner in this respect; and that the collar is made of cloth adapted to be laundried.

The button on the back of the shirt may be of any known form and attached to the shirt in any known manner.

What I claim as new and desire to secure by Letters Patent is—

1. A fold-collar comprising a band and a folded-over top with a tie-space therebetween at the back of the collar; said band being provided with the usual front and back buttonholes and having a buttonholed tab depending from the band below the back buttonhole therein, said folded-over top depending to cover said back buttonhole.

2. The combination with a shirt having a neckband and a button permanently attached to the back of the shirt below the neckband; of a laundried cloth collar having a band continuous from end to end thereof adapted to connect at its front with the neckband of the shirt in the usual manner and having at the back a buttonholed tab depending below the band adapted to receive said button on the shirt, said tab being permanently connected with the band of the collar.

3. The combination with a shirt having a neckband provided with a back buttonhole

and a button sewed to the back of the shirt below the neckband; of a cloth collar having a band continuous from end to end thereof adapted to connect at its front with the neckband of the shirt in the usual manner and having at the back a buttonholed tab depending below the band adapted to receive said button on the shirt, said band being provided with the usual back buttonhole adapted to receive a collar-button inserted through said back buttonhole in the neckband.

4. The combination with a shirt having a neckband provided with a back buttonhole and a button permanently attached to the back of the shirt below the neckband; of a cloth fold-collar having a band continuous from end to end thereof adapted to connect at its front with the shirt in the usual manner and having at the back a buttonhole adapted to receive a stud inserted through the back buttonhole of the neckband in the shirt, and having a folded-over top depending to cover the back buttonhole in the collar-band and having a tab permanently connected with the band of the collar and depending therebelow provided with a buttonhole adapted to receive said button on the back of the shirt.

In testimony whereof, I have hereunto set my hand this 15 day of January, 1912.

CHARLES F. POLK.
